SHOETREE

Edmund J. Baas, Rochester, N. Y.

Application March 11, 1935, Serial No. 10,577

3 Claims. (Cl. 12—128.4)

The present invention relates generally to forms for preserving the shapes of shoes, especially the toe portions thereof and has for its primary object the provision of a shoe-tree of this type having in connection therewith simple effective finger gripping means to facilitate placing the tree within, and removing the same from, a shoe.

More particularly my present invention while applicable to various types of shoes, is especially adapted for use in connection with more delicate types of shoes ordinarily worn by women, for instance, those either without effective heel portions to the uppers or without any heel portions to the uppers, and resides in a laterally expandable shoe-tree having spring expanding and guiding means, and having finger gripping means at the rear thereof which adds but slightly to its length and may be employed to greatly facilitate placement and withdrawal of the tree without in any way interfering with the ordinary expansion and adaptability of its parts.

With the above general objects in mind, my invention will be better understood and more thoroughly appreciated by reference to the accompanying drawing, illustrating the same, and forming a part of the specification. In this drawing:

Figure 1 is a perspective view illustrating the practical application of my invention.

Figure 2 is a top plan view of my improved shoe-tree, partly broken away and in section.

Figure 3 is a transverse vertical section taken therethrough substantially on line 3—3 of Figure 2, and

Figure 4 is a detail perspective view of a slightly modified form of the invention.

Referring now to these figures, my invention proposes a shoe-tree consisting of two laterally opposing substantially similar sections 10 and 11 which may move relative to one another and to a limited extent under the action of an expanding spring 12 between them, and will be guided in such movement by transverse forward and rear guide pins 13 and 14.

As shown particularly in Figures 2 and 3 the guide pins 13 and 14 are in the nature of screws, the threaded portions of whose shanks are firmly anchored as at 15 in the material of the section 11, and the shanks of which extend through bores 16 of the section 10, with the screw heads 17 movable in counterbores 18 of section 10.

The two sections 10 and 11 are also provided with opposed bores 19 located at points between 55 the guide pins 14 to receive the end portions of

the expanding spring 12 so as to avoid danger of ready displacement of the spring.

The shoe-tree as thus described, is, upon application to a shoe, first manipulated in the hands of the user so as to shift the two sections 10 and 13 into contacting relation against the tension of spring 12, and is then thrust into the toe portion of a shoe, such as the shoe 20 of Figure 1, so that upon release it is free to expand under the tension of spring 12 for the purpose of adapting itself to the normal form of the shoe within which it is used.

In order to facilitate the insertion of the last as above as well as its subsequent removal from the shoe 20, I may extend the sections 10 and 11 substantially rearwardly of the rear guide pin 14 and provide the opposing inner faces of these extended portions 21 with substantially-semi-circular vertically-disposed recesses 22, which recesses thus cooperate to form a vertically disposed finger opening, especially effective as such when the two sections are pressed into engagement with one another or nearly in engagement as they will be when in position in the shoe. It is thus an easy matter to reach into the shoe and by slipping the finger or fingers downwardly into the opening formed by the recesses 22, pull the tree rearwardly out of the toe portion of the shoe.

If a tree of less length is desired, I may dispense with the rearward extension 21 having the recesses 22 and instead terminate the two sections immediately at the rear of the rearmost guide pin 14, and in this instance utilize a ring-shaped finger gripping member 23 as in Figure 4, 35 extensions 24 of which will be apertured to receive the rearmost guide pin 14^a whereby the finger gripping ring 23 is supported in a manner permitting it to pivot upwardly and downwardly on the guide pin. This latter construction as shown in Figure 4 may be utilized in connection with a tree embodying sections 10^a and 11^a and be in this, as well as in other respects, the same as the above described shoe-tree except as to the particular finger gripping means.

What is claimed is:

1. A shoe-tree adapted in its effective position to be seated solely in the toe portion of a shoe, and consisting of a laterally expandable member in two side sections, guide pins extending between said sections and securely anchored at one end in one of the sections, the other section having bores to movably receive the shanks of the guide pins and counterbores within which the guide pins are headed to limit movement of the

sections away from one another, said sections having bores between the guide pins, a spring for expanding the member extending between said sections and having their ends projecting into the latter bores, each of said sections having a recess in its inner side adjacent to and spaced from, its rear end, the said recesses opposing one another rearwardly of the rearmost guide pin and forming a vertically disposed finger receiving aperture 10 facilitating disposition of the shoe-tree within, and its removal from, a shoe.

2. A shoe-tree comprising a member adapted to interfit the toe portion of a shoe, consisting of laterally relatively shiftable sections having co-

acting guide and expansion means, and having substantially semi-cylindrical recesses in their opposing sections adjacent to and spaced forwardly from the rear end of the member which together form a vertically disposed substantially cylindrical finger opening to assist in placing the tree within, and removing the same from, a shoe.

3. A shoe-tree comprising a two-part laterally-expansive member for disposition within the toe portion of a shoe, each part of which has a recess 10 in its inner face adjacent to and spaced from the rear end thereof and which two recesses together form a finger receiving aperture.

EDMUND J. BAAS.
